P.C.(57) **CLAIM**

The ornamental design for a touch panel control interface, as shown and described.

DESCRIPTION

FIG. 1 is a perspective view of the touch panel control interface in accordance with the present invention;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The broken lines in the drawings depict portions of the touch panel control interface that form no part of the claimed design.
